UNITED STATES PATENT OFFICE

154,088

DESIGN FOR A TOY ROLY-POLY OR SIMILAR ARTICLE

Constance Ray White, Beverly Hills, Calif.

Application April 16, 1948, Serial No. 145,763

Term of patent 7 years

(Cl. D34—4)

To all whom it may concern:

Be it known that I, Constance Ray White, a citizen of the United States, residing at Beverly Hills, in the county of Los Angeles and State of California, have invented a new, original, and ornamental Design, for a Toy Roly-Poly or Similar Article, of which the following is a specification, reference being had to the accompanying drawing, forming part thereof.

In the drawing

Fig. 1 is a front view of a toy roly-poly, showing my new design;

Fig. 2 is a rear view and Fig. 3 is a side view thereof.

I claim:

The ornamental design for a toy roly-poly or similar article, substantially as shown.

CONSTANCE RAY WHITE.
